SYLVANIA, A CORPORATION OF PENNSYLVANIA.

SLOW-ACTING DEVICE.

Application filed December 31, 1924. Serial No. 759,217.

To all whom it may concern:

Be it known that we, WALTER P. NEUBERT and WILLIAM E. SMITH, citizens of the United States, residing at Pittsburgh, in 5 the county of Allegheny and State of Pennsylvania, have invented certain new and useful Improvements in Slow-Acting Devices, of which the following is a specification.

10 Our invention relates to slow acting devices, and particularly to devices of this type which depend for their action on the flow of a fluid through a restricted orifice. Devices embodying our invention are well 15 adapted for use in connection with railway traffic governing apparatus, although they are not limited to this particular field.

16 We will describe one form of slow acting device embodying our invention, and will 20 then point out the novel features thereof in claims.

25 In the accompanying drawing, Fig. 1 is a view showing, in vertical section, one form of slow acting device embodying our invention. Fig. 2 is a sectional view along the line II—II of Fig. 1 illustrating the structure of the valve member 23 and associated parts. Fig. 3 is a bottom view of the slow 30 acting device illustrated in Fig. 1.

35 Similar reference characters refer to similar parts in both views.

the form here shown comprises a hollow

40 Referring first to Fig. 1, the device in cylindrical member 1, the lower rim of which is threaded to receive a plug 20. The cylindrical member 1 and the plug 20 constitute an outer fluid container which we will designate in general by the reference character O. Located inside of this 45 container is a hollow cylindrical member 4 mounted on plug 20, and comprising with this plug a second or inner fluid container which we will designate collectively as J. The upper end of member 4 is open and is located below the top of the outer container. Hence it follows that the two fluid 50 containers communicate with each other at the top, the opening between the two being of considerable area.

55 Located within the inner container J is a hollow cylindrical plunger 5 to which is attached a rod 6 extending upwardly and co-acting with the apparatus to be controlled by the device. The plunger is of such size

as to be movable in the container J with a 55 small amount of clearance. The inner and outer containers are filled to about the level indicated with a fluid 7 having sufficient specific gravity to float the plunger; this fluid is 60 preferably mercury.

65 The plug 20 is provided with a tapered valve seat 22 containing a frusto conical valve member 23. To insure a fluid-tight joint, valve member 23 is preferably ground into the seat 22. Valve member 23 is constantly urged against the valve seat by a spring 26, the tension of which is adjusted by a gland 27 threaded into the plug 20 and having a hole through which the stem 23^a of the valve projects. The valve member 23 is 70 provided, at its upper end, with a longitudinal bore 24 communicating with the inner container J. The wall of the valve member is further provided with a plurality of radially disposed apertures 25 of different 75 sizes, as best shown in Fig. 2. It will be plain from the drawing that the inner end of each of the apertures 25 opens into bore 24 and is therefore constantly connected 80 with the inner container J.

85 Plug 20 is also provided with a port 21 having one end opening, through the cylindrical member 4, into the outer container O. The other end of this port opens into the valve seat 22. The parts are so disposed that by rotating valve member 23 in its seat any selected one of the apertures 25 may 90 be moved into registration with the port 21. This movement of the valve member 23 may be conveniently accomplished by means of a handle 28 attached to the stem 23^a and provided with a pointer 28^a arranged to co-operate with indicia 29 on the outside of the plug 20 to show which of the apertures 25 is in registration with the port 21.

95 It will be apparent that when the plunger 5 is forced downwardly from the position in which it is illustrated, some of the fluid in the inner container, that is, some of the fluid between the plunger and the member 4, will be driven upwardly and will spill over into the outer container O. The downward movement of the plunger is not retarded to an appreciable extent because of the large opening between the two containers at the top of member 4. When the downward pressure on plunger 5 is removed, the fluid which was transferred from the inner to 100 105

the outer container returns through the port 21, one of the apertures 25, and bore 24 of valve member 23, and in so doing raises the plunger to its original position, that is, 5 to the position in which it is shown in the drawing. This return or upward movement is comparatively slow, however, because of the comparatively small area of the apertures 25, and of course the time required for the complete return movement of the plunger will vary according to the aperture 25 which registers with port 21.

It will be clear from the foregoing that 15 the time required for the upward movement of plunger 5 may be regulated from outside the device by proper manipulation of handle 28.

Although we have herein shown and described only one form of slow acting device 20 embodying our invention, it is understood that various changes and modifications may be made therein within the scope of the appended claims without departing from the spirit and scope of our invention.

Having thus described our invention, 25 what we claim is:

1. A slow acting device, comprising outer and inner fluid containers, a plunger within the inner container, fluid in said containers of sufficient specific gravity to float said plunger, said containers communicating with each other above the highest level of the fluid in the outer container, a passage connecting said containers below the lowest level of the fluid in the outer container, a valve member having a plurality of apertures of different sizes, and means for including any selected one of said apertures in said passage.

40 2. A slow acting device, comprising outer and inner fluid containers, a plunger within the inner container, fluid in said containers of sufficient specific gravity to float said plunger, said containers communicating with each other above the highest level of the fluid in the outer container, a passage connecting said containers below the lowest level of the fluid in the outer container, a valve member having a plurality of apertures of different sizes, and means operable from without said outer container for including any selected one of said apertures in said passage.

55 3. A slow acting device comprising outer and inner fluid containers, a plunger within the inner container, fluid in said containers of sufficient specific gravity to float said plunger, said containers communicating with each other above the highest level of the fluid in the outer container, a valve member having a plurality of apertures of different sizes, and means for connecting said containers together below the lowest level of the fluid in the outer container 60 through any selected one of said apertures.

4. A slow acting device comprising outer and inner fluid containers, a plunger within the inner container, fluid in said containers of sufficient specific gravity to float said plunger, said containers communicating with each other above the highest level of the fluid in the outer container, a port having one end opening into said outer container below the lowest level of the fluid in the container, a valve member provided with a plurality of apertures of different sizes, and means for moving said valve member to predetermined positions to connect the other end of said port with said inner container through any selected one of said apertures. 70 75 80

5. A slow acting device comprising outer and inner fluid containers, a plunger within the inner container, fluid in said containers of sufficient specific gravity to float said plunger, said containers communicating with each other above the highest level of the fluid in the outer container, a port having one end opening into said outer container below the lowest level of the fluid in the container, a valve member provided with a plurality of apertures of different sizes 85 and capable of assuming a plurality of positions in each of which positions the other end of said port is connected with said inner container through a different one of said apertures, and means outside of the outer container for indicating which of said apertures is co-operating with said port. 90 95

6. A slow acting device comprising outer and inner fluid containers, a plunger within the inner container, fluid in said containers of sufficient specific gravity to float said plunger, said containers communicating with each other above the highest level of the fluid in the outer container, a valve member having a plurality of apertures for connecting said containers together below the lowest level of the fluid in said outer container through any selected one of said apertures, and means outside of said outer container for indicating which of said apertures is interposed between said containers. 100 105 110

7. A slow acting device comprising outer and inner fluid containers, a plunger within the inner container, fluid in said containers of sufficient specific gravity to float said plunger, said containers communicating with each other above the highest level of the fluid in the outer container, a valve member having a plurality of apertures of different sizes all constantly connected with said inner container, and means for connecting any selected one of said apertures with said outer container below the lowest level of the fluid therein. 115 120 125

8. A slow acting device comprising outer and inner fluid containers, a plunger within the inner container, fluid in said containers of sufficient specific gravity to float said plunger, said containers communicating 130

with each other above the highest level of the fluid in the outer container, a tapered valve seat in the bottom of said inner container, a frusto-conical valve member having a central longitudinal bore communicating with said inner container and a plurality of radial apertures all opening into said bore, means for constantly urging said valve member into said valve seat, a port having one end constantly connected with said outer container below the lowest level of the fluid in such container, and means for turning said valve member to connect any selected one of said apertures with the other end of said port from outside the outer container.

9. A slow acting device comprising outer and inner fluid containers, a plunger within the inner container, fluid in said containers of sufficient specific gravity to float said plunger, said containers communicating with each other above the highest level of the fluid in the outer container, a port having one end opening into said outer con-

tainer below the lowest level of the fluid in the container, a valve member provided with a plurality of apertures of different sizes all constantly connected with said inner container, and manually operable means for moving said valve member to bring any selected one of said apertures into registration with said port.

10. A slow acting device, comprising outer and inner fluid containers, a plunger within the inner container, fluid in said containers of sufficient specific gravity to float said plunger, said containers communicating with each other above the highest level of the fluid in the outer container, and a passage connecting said containers below the lowest level of the fluid in the outer container and including any selected one of a plurality of apertures of different sizes.

In testimony whereof we affix our signatures.

WALTER P. NEUBERT.
WILLIAM E. SMITH.
